RIB-TRIMMING MACHINE FOR INNERSOLES ~~EST AVAILABLE COPY~~

1,070,069.

Specification of Letters Patent.

Patented Aug. 12, 1913.

Application filed July 5, 1912. Serial No. 707,796.

To all whom it may concern:

Be it known that I, GEORGE L. ROLLINS, a citizen of the United States, and resident of Bridgewater in the county of Plymouth 5 and State of Massachusetts, have invented certain new and useful Improvements in Rib-Trimming Machines for Innersoles, of which the following is a specification.

The object of the present invention is to 10 provide a machine for trimming to a uniform height the rib which is provided on one of the faces of an inner sole to receive the stitches which unite the upper and welt to the inner sole.

15 It is a common practice to form such a rib in part by cutting a channel in the face of the inner sole and turning up the flap so produced, and in part by a reinforcing strip or sheet of fabric laid on the sole adjacent 20 to such upturned flap and bent up at its edge beside the flap, and the machine in which my present invention is embodied is designed to trim a rib so formed as well as those otherwise produced.

25 A practical means for accomplishing the foregoing objects is contained in the machine described in detail in the following specification and illustrated in the accompanying drawings, which machine embodies 30 the invention in the best form now known to me.

In the drawings, Figure 1 is a front elevation of the machine referring to Fig. 2 is 35 a side elevation as seen from the left of Fig. 1; Fig. 3 is a plan view; Fig. 4 is a sectional view of the parts of the machine which directly act upon the sole.

The same reference characters indicate the same parts in all the figures.

40 Referring to the drawings, the characters 10, 11, and 12 represent legs and a plate, which, together constitute a base or pedestal adapted to be placed on the floor and having a proper height. On the base is secured a head 13 having bearings in which is rotatably mounted a shaft 14. This shaft carries at one end a disk 15 secured immovably by a set screw 16 or other suitable means, and at its other end carries a sprocket wheel 50 17 which is driven by a chain 18 from a sprocket 19 in a main shaft 20, which latter is supported in bearings 21 and 22 forming parts of brackets which are secured to the side of the base as shown in Figs. 2 and 3. 55 Shaft 20 carries belt pulleys 24 and 25 one

of which is fast and the other loose for applying power thereto in the usual way.

The disk 15 is one member of a work feeding couple, and is in substance a feed wheel or roll. The complementary member of this 60 couple is a disk or wheel 26 carried by a shaft 27 which is held in bearings 28 and 29 on a holder 30 pivotally connected with the head 13 by a stud 31, shown in dotted lines in Fig. 1. Shaft 27 carries a gear wheel 32 (Fig. 1) which lies below and meshes with a gear wheel 33 on the shaft 14. A positive drive is thus given to both feed rolls, and as the ratio of the gear wheels 32 and 33 is approximately the same as the ratio between 70 the diameters of feed wheels 15 and 26 the latter have substantially the same peripheral speed. Owing to the movable mounting of holder 30 which carries wheel 26, the latter may yield in order to accommodate inequalities in thickness of the rib of an inner sole, and is yieldingly pressed toward the wheel 15 by a spring 34, which acts against the holder 30 and reacts against an adjustable abutment screw 35 threaded through a lug 80 36 on the side of the head. The pivot of the holder 30 is in the plane of the gears 32 and 33 in order to permit as wide separation of disk 26 from wheel 15 as may be necessary without separating the gears. The limits of movement of disk 26 are established by a stop screw 37 adjustably threaded through a lug 38 on the holder 30 and a second stop screw 39 rigid with the head and underlying 85 the bearing 28. 90

The cutter for trimming the rib is a disk 40 secured, preferably as shown in Fig. 4, to a sleeve 41 which is loose on the shaft 14, and to which is secured a gear 42. This cutter or trimmer lies close against the inner 95 face of the wheel 15 and is of larger diameter than the latter so that it overlaps the complementary disk 26. Thus, when the rib of an inner sole is inserted between the feed members 15 and 26, as shown in Fig. 4, whatever 100 parts of the rib are high enough to extend beyond the feed members intersect the plane of the knife and are trimmed off thereby. A presser roll 43 is arranged in a plane 105 transverse to that of the feed wheels and including the line of feed, so as to bear on the unribbed face of the inner sole and hold the ribbed face close against the feed wheels. This presser roll is journaled on a stud 44 as 110 carried by a bell crank lever 45 pivoted at

46 to an arm 47 on the head, and pressed yieldingly toward the feed rolls by a spring 48 surrounding a rod 49 and reacting between the top of the base and a collar 50 adjustably secured to said rod. The rod is 5 pivotally connected at 51 to one arm of the bell crank lever, and is of sufficient length to permit its other end to be connected with a treadle (not shown) near the floor whereby it may be depressed to swing the presser roll away from the feed rolls to permit placing of the work. A stop screw 51^a threaded through a lug 52 on the head is in position to engage an arm of the bell crank and limit the inward movement of the presser roll.

15 The cutter is rotated in the same direction as the adjacent feed wheel 15 but at a higher rate of speed by a system of back gearing consisting of a shaft 53, a small gear 54 secured to said shaft and meshing with gear 33 on shaft 14, and a large gear 55 on shaft 53 meshing with the gear 42, which, as previously stated, is rigidly connected with the cutter. Shaft 53 is held in bearings 56 and 57 on the side of the head 13.

20 It will be evident that this mode of operating the knife causes it to make a drawing cut, which is especially effective in severing the fibers of the textile fabric used to support the rib in a reinforced inner sole. The 25 disk 26, of which one face is close to the edge of the knife, supports that part of the rib acted upon by the knife and serves as one member of a shear, but in addition to 30 the shearing action the more rapid movement of the knife edge in the direction of feed causes the knife to be drawn along the rib, whereby clean cutting of the rib throughout its entire length is assured. The 35 importance of this feature can hardly be over emphasized, since in all other machines of which I have knowledge that are adapted to trim off the ribs of inner soles, the operation is defective in that the cloth is cut 40 raggedly. Mine is the only machine of 45 which I have knowledge in which a drawing action of the knife is provided which insures a clean and even cut under all conditions, even though the knife should not be 50 in perfect condition and the reinforcing fabric should be wet.

Located near the knife is a grinding wheel 58 secured to a shaft 60 which is carried in bearings on a pivotally mounted holder 61, 55 the pivot of which is a stud 62 held in a bracket 63 on the head. Another stud 64 for guiding the holder at the end where the grinding wheel is located passes through a slot 65 in the bracket. A handle 66 is fastened to an arm 67 of the grinding wheel holder and projects through a slot in the head to the front side of the machine, where it may be engaged and so moved as to bring the grinding wheel against the knife, such 60 grinding wheel being normally held away

from the knife by a spring 68 connected to the handle 66 and so arranged as to pull away from the knife. The driving means for the knife comprises a belt 69 passing around a pulley on the grinder shaft 60 and around a pulley 71 on the main shaft 20. Guide pulleys 72 and 73 are mounted on the brackets 74 in proper positions to bend the belt into the planes of the pulleys. The grinding wheel is located in a plane transverse to the plane of the knife, and intersecting the circle of the knife a short distance within its circumference, and it is located at such a position in this plane as to bear on the bevel adjacent to the edge of the knife when brought into operative position. It is also driven in such a direction of rotation that its portion which engages the knife travels oppositely to the portion of the knife with which it is engaged. The result is that the minute scratches made in the knife by the abrasive are inclined to the edge of the knife backwardly, or at an acute angle to the direction in which the edge travels. Thus the microscopic irregularities in the knife edge are inclined forwardly in a manner such as to enter the work first, producing an effect somewhat like that of a circular saw, which is exceedingly effective in severing the reinforcing fabric.

95 The height of the rib left after cutting is determined by the thickness of the disk 26 and wheel 15. A feature of the construction having particular value is that the outer face of the disk 26 is made convex or crowning as shown in Figs. 1 and 4, such crowning face being adapted to engage the surface of the inner sole inside the rib and thereby prevent the edge of the disk, when the inner sole is first fed into the machine, from catching the edge of the reinforcing layer and pulling it away from the body of the inner sole.

100 I claim:

1. A machine for the purpose indicated, 110 comprising in combination a pair of feed disks adapted to receive between them the rib of an innersole, and a disk knife rotating adjacent to and independently of said feed disks in position to cut the portion of the lip extending beyond the feed disks, one of said disks having an edge crossing the edge of the knife and constituting a complementary shear member.

115 2. A machine for the purpose indicated, comprising in combination a pair of feed disks adapted to receive between them the rib of an innersole, a disk knife rotating adjacent to said feed disks with its edge crossing and substantially in contact with an 120 edge of one of the feed disks in position to cut the portion of the lip extending beyond the feed disks, and means for driving said disk knife at a faster rate than the rate of 125 the feed disks.

3. A trimming machine comprising coöperating feed disks, and a disk cutter mounted coaxially with one of said feed disks and having its sharp edged periphery extending 5 beyond the periphery of the said feed disk, and being driven independently of said disk.

4. A trimming machine comprising coöperating feed disks, a disk cutter mounted coaxially with one of said feed disks and having its sharp edged periphery extending 10 beyond the periphery of the said feed disk, means for driving said feed disks simultaneously in opposite directions of rotation at the same peripheral speed, and means for 15 rotating the cutter at a higher peripheral speed.

5. A machine for trimming the stitch-receiving rib of an innersole, consisting essentially of complementary rotary feed members 20 arranged to grasp such rib between them and a cutter coaxial with one of said members and overlapping the other member substantially in contact with an edge thereof, arranged on the side of such members opposite from that on which the body of the innersole lies, for severing the stock of the 25 rib projecting beyond said members.

6. A machine for trimming the stitch-receiving rib of an innersole, consisting essentially of complementary feed members arranged to grasp such rib between them, means for positively moving the gripping portions of both said feed members in unison in the direction of feeding, a cutter arranged on the side of such members opposite from that on which the body of the 30 innersole lies, extending partly across both members at the point where such members grip the rib, for severing the stock of the rib 35 projecting beyond said members, and means for driving said cutter in the same general direction as one of said feed members and at a higher speed.

7. A machine for trimming the stitch-receiving rib of an innersole, consisting essentially of complementary feed rolls arranged to bear on opposite sides of such rib, means for driving said rolls positively in opposite directions of rotation so that their rib-gripping portions move in the same direction, a presser arranged to bear on the outer face 40 of the sole and yieldingly pressed toward said rolls opposite to the nip thereof, and

a cutter arranged close to the faces of the rolls opposite to the presser for cutting off 55 such portions of the rib as extend beyond the rolls.

8. A trimming machine including complementary feed rolls arranged in substantially the same plane and on substantially parallel 60 axes sufficiently near together to grasp the work between them, one of said rolls being movable away from the other and yieldingly pressed toward such other, driving means arranged for turning said rolls in relatively 65 opposite directions of rotation, a disk knife mounted rotatably close beside the end face of one of said rolls and overlapping the adjacent portion of the opposite roll, and means for driving the knife in the same relative 70 direction as the roll beside which it is placed; and at a higher peripheral speed, whereby to sever with a drawing cut the stock which is fed by the rolls.

9. A machine for trimming the stitch-receiving rib of an inner sole, consisting of combined feeding and gaging members arranged to grip such rib between them, a means bearing on the face of the inner sole opposite to that from which the rib projects, 75 for holding the rib up to said members, means for driving said member rotatably in unison, a rotary disk knife extending partly across the faces of both said members near the point where they grip the rib 80 and at the side of such members from which the rib projects, and means for rotating said disk knife independently of the feed members.

10. An insole rib trimming machine comprising essentially coöperating feed rolls adapted to grip the rib of the insole between them, a disk knife mounted coaxially with one of said rolls and extending across the complementary roll in substantial contact 95 with a face thereof, whereby said complementary roll constitutes also a rest for a shear member complementary to the knife, and means for driving the knife independently of the rolls.

In testimony whereof I have affixed my signature, in presence of two witnesses.

GEORGE L. ROLLINS.
